UNITED STATES PATENT OFFICE.

CARL S. SMITH, OF ALBANY, NEW YORK.

INTERNAL-COMBUSTION ENGINE.

1,183,687.

Specification of Letters Patent. Patented May 16, 1916.

Application filed September 9, 1914. Serial No. 860,927.

To all whom it may concern:

Be it known that I, CARL S. SMITH, a citizen of the United States, residing at Albany, in the county of Albany and State of New York, have invented new and useful Improvements in Internal-Combustion Engines, of which the following is a specification.

This invention relates to improvements in internal combustion engines and has particular application to an engine wherein the ordinary carbureter and usual ignition system are dispensed with, the gasolene being admitted, in a raw state, to the compression space of the motor and ignited instantly by coming into contact with air previously admitted to the cylinder and compressed to a high degree therein by the action of the piston.

In some types of internal combustion engines the gasolene is delivered to the combustion chamber in the cylinder from a supply tank through a gasolene intake valve controlled by the engine and under pressure from a pump driven by the engine and in communication with the supply tank. In carrying out the present invention, it is my purpose to eliminate the engine driven gasolene-controlling valve and interpose the pump in the connection between the supply tank and the combustion chamber of the cylinder so that in one stroke of the piston of the pump the gasolene will be drawn into the pump and in the other stroke of the piston such gasolene will be delivered to the cylinder under pressure, suitable check valves being employed at opposite sides of the pump to eliminate back pressure.

It is also my purpose to improve and simplify the general construction of engines of the type described and to provide an engine wherein the component parts will be so arranged and correlated as to reduce the possibility of derangement to a minimum and insure the proper operation of the engine under all conditions.

With the above and other objects in view, the invention consists in the construction, combination and arrangement of parts hereinafter set forth in and falling within the scope of the claim.

In the accompanying drawing; Figure 1 is a vertical sectional view through an engine embodying the present invention. Fig. 2 is an enlarged longitudinal sectional view through the pump. Fig. 3 is a longitudinal sectional view through the injector nozzle.

Referring now to the drawing in detail, 1 designates one of the cylinders of a motor, 60 while 2 indicates the piston within such cylinder capable of reciprocatory movement therein, such piston and cylinder being of the usual construction and the cylinder being connected to and extending upwardly 65 from the usual two-part crank case 3. Journaled in the opposite end wall of the crank case 3 is a crank shaft 4 connected with the piston 2 by means of the usual pitman or connecting rod 5. Each cylinder of 70 the motor is provided with a T-head 6 carrying an air inlet valve 7 at one side thereof and an exhaust valve 8 at the opposite side. These valves are shown as having the stems 9 and 10 thereof mounted in 75 housing sleeves 10' to render the same quiet in operation. 11 indicates the valve lift rods that are actuated from underlying cam shafts 12 and 13, as usual. The arrangement thus far described is the ordinary construction now embodied in automobile 80 motors.

In the practice of my invention, I dispense entirely with a carbureter and the usual ignition apparatus embodying spark 85 plugs or contact points. In place thereof I employ an injector nozzle 14 in which is arranged a check valve 15, such nozzle being preferably located directly above the piston 2 and having connected therewith a 90 gasolene feed pipe 16 that extends downwardly along one side of the engine and is connected with a suitable source of gasolene supply 18. The feed pipe 16 is preferably of two sections and connected in such pipe 95 at the meeting ends of the sections thereof is a cylinder 17 connected with the adjacent side wall of the crank case and extending outwardly therefrom. Mounted within the cylinder 17 and adapted to reciprocate 100 therein is a piston 18 connected through the medium of a connecting rod 19 with the strap of an eccentric 20 fixed upon the adjacent cam shaft 13 and adapted to rotate with such shaft. Interposed in the section 105 of the pipe between the cylinder 17 and the supply tank 18' is a check valve 21 whereby back pressure from the pump, composed of the cylinder 17 and piston 18, into the source of supply is avoided, while located 110 in the pipe section connecting the pump cylinder with the injector nozzle 14 is a

check valve 22 coöperating with the check valve 15 to prevent back pressure from the combustion chamber in the cylinder. The eccentric 20 is so arranged as to properly 5 time the movement of the piston 18 of the pump with respect to the piston 2 of the motor.

From the foregoing description taken in connection with the accompanying drawing, 10 the construction and operation of the motor will be readily understood. As the piston 2 moves upwardly within the cylinder 1, the fresh air taken through the inlet 9 controlled by the valve 7 is highly compressed 15 in the upper part of the cylinder and when the piston reaches the limit of its movement in an upward direction the eccentric moves the piston 18' toward the outer end of the cylinder 17 thereby compressing the 20 liquid gasoline previously drawn into the cylinder and forces such liquid through the upper section of the intake pipe 16 and injector nozzle 14 into the upper end of the cylinder 1. As soon as the gasoline comes 25 into contact with the highly heated air in the combustion chamber, ignition takes place and the piston 2 is driven downward. Upon the return movement of the piston the 30 exhaust valve 8 is opened and the gas passes outward therefrom through the exhaust port of the engine. It has been found by actual test and experiment that only a few turns of the crank shaft are necessary in order to cause the ignition of the compressed gas in 35 the cylinder, this being due to the fact that the air in the compression or combustion chamber, on the compression stroke of the piston is highly compressed, owing to the long stroke of such piston.

40 It will be noted that the pump composed of the cylinder 17 and piston 18 is located exteriorly of the engine, enabling ready

access to be had thereto for the purpose of removing sediment or water which may collect in the cylinder or be contained in the 45 feed pipe, it being a comparatively simple matter to detach the sections of the feed pipe from the cylinder 17 and remove the cylinder from the crank case. By means of this construction the feed pipe may be 50 blown out when necessary so as to remove any foreign matter therefrom.

Furthermore, it will be noted that the pump composed of the cylinder 17 and piston 18 acts not only as a pump but also as a 55 controlling valve in that a predetermined quantity of liquid fuel is delivered to the combustion chamber of the cylinder at predetermined intervals.

I claim:

In a device of the class described, in combination a crank case, said crank case having a side opening a cam shaft in said case opposite said opening, a valve operating cam on said shaft, said cam being eccentric, a circular strap loosely engaging said eccentric, an extension arm secured upon said strap and tapering toward its outer end, and projecting through said opening, a cylinder having an outer flaring part secured to said 70 case having its largest diameter equal to that of said opening and registering therewith, a piston in said cylinder, and a lug on said piston pivotally connected to said extension arm, said arm adapted to tilt at 75 opposite points relative to the axis of said piston toward the walls of said flaring portion of said cylinder.

In testimony whereof I affix my signature in presence of two witnesses.

CARL S. SMITH.
